(57) **CLAIM**

The ornamental design for switchgear, as shown and described.

DESCRIPTION

FIG. 1 is a three-dimensional view generally from the top right rear of an embodiment of switchgear in its switch-closed configuration;

FIG. 2 is a three-dimensional view generally from the top left rear thereof;

FIG. 3 is a three-dimensional view generally from the bottom right rear thereof;

FIG. 4 is a left side view thereof;

FIG. 5 is a right side view thereof;

FIG. 6 is a top view thereof;

FIG. 7 is a bottom view thereof;

FIG. 8 is rear view thereof;

FIG. 9 is front view thereof;

FIG. 10 is a three-dimensional view generally from the top right rear of the switchgear in its switch-open configuration;

FIG. 11 is a three-dimensional view generally from the top left rear thereof;

FIG. 12 is a three-dimensional view generally from the bottom right rear thereof;

FIG. 13 is a left side view thereof;

FIG. 14 is a right side view thereof;

FIG. 15 is a top view thereof;

FIG. 16 is a bottom view thereof;

FIG. 17 is rear view thereof; and,

FIG. 18 is front view thereof.
